UNITED STATES PATENT OFFICE.

EDGAR J. REILLY, OF YOUNGSTOWN, OHIO, ASSIGNOR TO THE WILLIAM B. POLLOCK COMPANY, OF YOUNGSTOWN, OHIO, A CORPORATION OF OHIO.

HOT-METAL CAR.

Continuation of application Serial No. 331,057, filed May 13, 1920. This application filed April 20, 1922.
Serial No. 555,775.

To all whom it may concern:

Be it known that I, EDGAR J. REILLY, a citizen of the United States, residing at Youngstown, county of Mahoning, and State of Ohio, have invented a new and useful Improvement in Hot-Metal Cars, of which the following is a full, clear, and exact description.

The present invention relates broadly to 10 cars or carriers for molten metal or other materials, and more particularly to cars intended for hot metal, cinders and the like.

An important object of the present invention is to provide a compactly designed car 15 having both increased capacity and strength due to the provision of a containing cavity of novel design.

In the art of handling molten metal in cars 20 of this general type, it is desirable to maintain the mass of molten metal in as compact a form as possible, whereby heat radiation is reduced and the fluidity of the metal maintained.

In the accompanying drawings there are 25 illustrated certain forms of containers particularly adapted for transporting molten materials, which containers are adapted to be easily charged and discharged and are adapted to maintain the metal against chilling. It will be understood that the drawings are illustrative only and that changes 30 may be made in the construction and operation of the hot metal cars illustrated without departing from the spirit of the invention or the scope of my broader claims.

In the drawings,—

Figure 1 is a top plan view of one form of hot metal car embodying the present invention;

Figure 2 is a side elevation of the construction illustrated in Figure 1;

Figure 3 is a transverse section through the hot metal car;

Figure 4 is a section similar to Figure 3, 45 illustrating a slightly modified form of the invention;

Figure 5 is a side elevation of still another form of hot metal car embodying the invention; and

Figure 6 is a transverse sectional view 50 through the construction illustrated in Figure 5.

This invention provides a carrier of large

capacity for distributing hot metal from a blast furnace to the required point of disposition about steel works or foundries, such as mixers, pig casting machines, molds, etc., or for general storage or transfer purposes in metallurgical plants generally.

It is desirable that carriers of this general nature be constructed as compactly as possible without interfering with the strength or capacity thereof. As the carriers are frequently adapted to receive and transport as high as seventy-five or more 60 tons of material at a time, the importance of these features will be apparent. I have found that all of these desirable features may be produced by constructing a container which is generally circular in transverse section and which presents shapes of substantially similar outline in every section including the longitudinal axis of the container, in which the last mentioned sections are of 65 decreasing width from the center of the container toward each end thereof.

Referring more particularly to Figures 1 to 4 of the drawings, there is illustrated a hot metal car construction comprising a container having a main body portion 5 which 70 may consist of a suitable refractory lining 6 and an outer enclosing metal sheet or casing 7. In order to provide a construction of the required strength, the body of the container or the cavity therein may be so formed 75 as to present sections which are substantially circular in any plane extending transversely of the container. This provides a container which is curved or arched in transverse section, thereby insuring maximum strength. 80 At the same time, this shape facilitates discharging of the container as the contents thereof readily follow the contour of the refractory lining. These desirable results may further be insured by providing a cavity within the container of such shape that 85 all of the sections including the longitudinal axis are of similar outline. It will be apparent that these sections are of maximum width at the central portion of the container, and of gradually decreasing width toward 90 each end thereof.

The body 5 of the container may have secured thereto in any desired manner suitable trunnions 8 adapted to permit the container 105 to be mounted on suitable trucks or sup-

ports in accordance with the practice in this art.

In the form of the container illustrated in the first three figures of the drawings, there is provided a single discharge opening 10 extending substantially the entire width of the container and provided with oppositely disposed pouring lips 11. As illustrated in Figure 4, however, I may construct the container with a plurality of independent pouring openings 12. In some cases, each of the pouring openings may be provided with a suitable lip 13 over which the material may be discharged.

In Figures 5 and 6 of the drawings there is illustrated a slightly modified form of the invention in which the main body 5' of the container comprises a substantially cylindrical enclosing shell 7' with a refractory lining 6'. The ends 9' of the container may be similarly constructed. The refractory lining 6' in the container is so shaped that all of the transverse sections therethrough are substantially circular in outline, while all longitudinal sections including the longitudinal axis of the container are of similar outline and of decreasing width from the center toward either end. The ends of the container may carry supporting trunnions 8' of suitable construction.

It will be apparent that a container of this construction embodies broadly the advantageous features already referred to although the sections including the longitudinal axis are not entirely bounded by curved lines.

In Figure 6 the modified form of container is illustrated as being provided with independent pour-out openings 12' having pouring lips 13'.

The advantages of the present invention arise from the provision of a container of the character referred to whereby the contents thereof are maintained in a compact mass and are easily discharged therefrom.

The shape of the container, due to the fact that it is circular in every transverse section permits the same to be easily rotated to effect discharge therefrom while insuring a maximum strength in every position to which it may be rotated.

I make no claim in this application to the specific shape of container shown in Figures 1 and 2, as this particular shape of container forms the subject matter of Patent No. 1,438,661, granted to Alfred C. Nelson and Edgar J. Reilly on December 12, 1922, on an application filed May 13, 1920, Serial No. 381,057.

I claim:

1. A hot metal car, comprising a container having a cavity circular in every transverse section therethrough, and presenting shapes of substantially similar outline in every section including its longitudinal axis, said last mentioned sections all being of decreasing width from the center toward each end thereof, substantially as described. 60

2. A hot metal car, comprising a rotatable container having its transverse axis of greatest length at its central portion and intersecting the axis of rotation, said container having its interior wall arched both transversely and longitudinally and being substantially symmetrical on both sides of either the transverse or the longitudinal axis, substantially as described. 70

3. A hot metal car, comprising an elongated container rotatable about a longitudinal axis of greater length than its transverse axis, said container presenting arched walls defining every section either transversely or longitudinally therethrough, and being substantially symmetrical on both sides of either of said axes, substantially as described. 80

4. A hot metal car, comprising a container having a cavity therein with the walls defining any transverse section through said cavity of substantially uniform curvature, and the walls defining longitudinal sections all of which decrease in width from the center toward either end thereof, substantially as described. 90

5. A hot metal car, comprising a rotatable container having its transverse axis at its central portion and having its major longitudinal axis also at its central portion and intersecting said first named axis, said container being rotatable about a longitudinal axis, said transverse axis and said major longitudinal axis both decreasing in length in every section displaced with respect to said transverse or longitudinal central portions respectively, substantially as described. 95

6. A hot metal car, comprising a rotatable container having its transverse axis at its central portion, and having its major longitudinal axis also at its central portion and intersecting said first named axis, one of said axes forming the axis of revolution of said container, said axes decreasing in length in every section displaced with respect to said transverse or longitudinal central portions respectively, substantially as described. 100

In testimony whereof I have hereunto set my hand.

EDGAR J. REILLY.
